BRAKING MEANS FOR DUAL WHEELS

Charles S. Ash, Milford, Mich.

Application October 12, 1939, Serial No. 299,087

11 Claims.

(Cl. 188—18)

The present invention relates to new and useful improvements in the braking of independently rotatable dual wheels such as are used for automotive road vehicles.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Figure 1 is a vertical sectional view showing a typical and illustrative embodiment of the braking means of the present invention as applied to the dual dirigible wheels of an automotive vehicle;

Figure 2 is a fragmentary sectional view, with certain parts broken away and taken on the line 2—2 of Figure 1;

Figure 3 is a detailed fragmentary section taken on the line 3—3 of Figure 2;

Figure 4 is a detailed fragmentary section taken on the line 4—4 of Figure 3;

Figure 5 is an end elevation, with certain parts broken away, of the expandable braking means of the present invention;

Figure 6 is a similar view of a modified form of expandable braking means; and

Figs. 7 and 8 are detailed sectional views taken on lines 7—7 and 8—8 of Fig. 2.

The present invention has for an object the provision of a novel and improved self-energized or servo-braking mechanism for independently rotatable dual wheels. A further object of the invention is the provision of an improved brake of the servo type which operates positively and equally on each of two independently rotatable dual wheels. Still another object of the invention is the provision of an improved self-energized brake shoe assembly which may be interchangeably replaced for a non-servo brake shoe assembly in certain types of brakes for independently rotatable dual wheels.

In the illustrative embodiment of the present invention, the braking means for the coaxial independently rotatable dual wheels comprises a pair of spaced-apart brake members which are preferably of disc-like form and are provided with braking surfaces facing each other, one of these brake members being attached to each of the wheels and the two brake members being

rigidly held on their wheels in coaxial relation. Between the spaced-apart brake members are positioned a pair of relatively movable cooperating brake members which may be separated or 5 axially expanded so as to contact with the rigidly mounted brake members, and these cooperating brake members are preferably so mounted and interconnected that they exert equal pressure on the rigidly mounted brake members, and upon 10 contact with one or the other of the rotating rigidly mounted brake members, they are further expanded so as to increase the braking effort and thereby reduce the exertion required on the part of the operator for the application of the brakes. As embodied, the cooperating expandable brake members are interconnected by means of spiral gears or oppositely faced wedge surfaces so that their relative rotation is translated into axial expansion or contraction, and the 15 initial relative rotation may be produced by means of a relatively small fluid pressure operated motor mounted on the brake members.

It will be understood that the foregoing general description and the following detailed description as well are exemplary and explanatory of the invention but are not restrictive thereof.

Referring now in detail to the illustrative embodiment of the invention as shown by the accompanying drawings, the invention is shown as applied to the braking of a pair of dual dirigible wheels such as are used for the steering of an automotive vehicle. At the end of the front axle 10 is mounted a king pin 11 by which the forked spindle end 12 is pivotally supported. A wheel hub 15 is mounted for rotation on the spindle end 12 by means of the tapered roller bearings 16 and 17, and the outer wheel 18 provided with a pneumatic tire supporting rim 19 is bolted to the hub by means of the cap screws 20. The inner wheel 25 provided with its tire supporting rim 26, is independently rotatably mounted on hub 15 by means of inner wheel hub 28, suitable bearings 29 and 30 being provided between the hubs. The inner wheel 25 is preferably formed with a relatively deep dish to space the rims 19 and 26 the correct distance apart, at the same time permitting the king pin 11 to be located between the points of contact at the tires with the road, and also providing a relatively enclosed space for the mounting of the braking mechanism for both wheels.

Spaced apart coaxial braking surfaces are rigidly attached to the inner and outer wheels, and as embodied a brake disc 40 having a flat braking surface 41 is attached to the inner end of outer wheel hub 15 by means of a flange 42 at the inner edge of the brake disc 40 and cap screws 43. A brake disc 46 having a flat braking surface 47 of substantially the same dimensions as surface 41 is attached to the inner portion of the

inner wheel 25 by means of the external flange 48 and cap screws 49. Thus, the brake surfaces 41 and 47 face towards each other, are coaxial with respect to each other and the wheels 18 and 25, and are fixedly held in parallel planes but at the same time are capable of independent rotation.

Cooperating expandable braking means are provided between the spaced apart brake surfaces 41 and 47, and comprise a pair of rings 50 and 51, substantially U-shaped in cross-section, with their open sides facing each other, the two rings being of substantially the same external diameter. The opposing faces of rings 50 and 51 are preferably flat and substantially parallel with each other, and are each provided with a disc or brake lining 53 firmly secured thereon, the dimensions of the brake lining corresponding generally to the dimensions of the surfaces 41 and 47.

Means are also provided for anchoring the expandable braking means against rotation, at the same time permitting it to move axially of the wheels so that the braking pressure may be evenly distributed between the wheels and as embodied, ring 50 is formed with a pair of diametrically opposed rectangular recesses 55 which receive anchor pads 56. Pads 56 are rotatable about the king pin 11 but are held against rotation with the wheels by means of their cylindrically recessed faces which fit over the upper and lower fork members of spindle 12 and are retained thereon by cap screws 58 so as to form dust excluding caps for the king pin.

Means are provided for expanding the brake shoes 50 and 51 into contact with the braking surfaces 41 and 47, and for energizing the brake by the rotation of the wheels. As embodied, an internal spiral or helical gear 60 is provided with spacing lugs 61 by which and screws 62 it is mounted within the U-shaped interior of brake shoe 50, and this gear 60 meshes with a similarly pitched external spiral or helical gear 63 of ring shape which is fastened to the brake shoe 51 by spacing lugs 64 and screws 65. As one of the brake shoes 50 and 51 is rotated relative to the other, the other shoe being held against rotation, the ring gears 60 and 63 are similarly rotated and the spiral tooth formation of these gears transforms this relative rotation into axial expansion or contraction of the brake shoes 50 and 51, so as to engage or disengage the brake shoes with the braking surfaces 41 and 47.

The gear teeth of gears 60 and 63 may, of course, be of opposite hand on opposite sides of the vehicle, so that as the brake shoe 51 is brought into contact with the braking surface 47, continued rotation of the wheels in a forward direction will cause further expansion of the brake shoes 50 and 51 to increase their braking effort. However, gears of similar hand may be employed if the brake shoe having limited rotational movement engages the inner wheel brake surface on one side of the vehicle and the outer wheel brake surface on the other side of the vehicle.

Means are provided for initially expanding the brake members 50 and 51 into engagement with the brake surfaces 41 and 47, and for this purpose a relatively small hydraulic cylinder 70 having a piston 71 is mounted on a bracket 72 extending from the brake shoe 51, and piston 71 engages in a cup-shaped recess 74 in a bracket attached to the brake shoe 50. Hydraulic brake actuating fluid is supplied to the piston 70 in the usual manner to conduit 75, and as the pressure is increased, the brackets 72 and 74 are moved

apart causing relative rotation between gears 60 and 63 and thereby causing axial expansion of the brake shoes in contact with the braking surfaces 41 and 47 so that the servo action of the brakes may be initiated.

Means are also provided for retracting the brakes to their released position as soon as the pressure is relieved in the cylinder 70, and for this purpose a spring 76 is compressed between the brackets 77 and 78 attached to the brake shoes 50 and 51 respectively. Means are also provided for holding the retracted brake shoes 50 and 51 in a relatively definite position so as to prevent their rubbing against the surfaces 41 and 47. For this purpose, the spindle fork 12 is formed with a spider having projecting arms 80 which are apertured to receive the threaded studs 81 which are threaded into brake shoe supporting lugs 83 carried by the brake shoe 50 on its inner surface. A spring 84 is compressed between washer 85 and arm 80 and the washer is held on the stud 81 by means of cotter pin 86. A ratchet wheel 88 cooperating with the detent spring 89 permits the brake shoes 50 and 51 to be shifted axially of the brake assembly and out of contact with the surfaces 41 and 47 when the brakes are fully retracted, and this adjustment may be obtained by turning the studs 81 through their squared heads 90. A pair of tension springs 91 carried by pins secured in brake shoes 50 and 51 serves to maintain the brake shoe 51 retracted laterally against brake shoe 50 and thus out of contact with surface 47 when the brake is not in use.

Figure 6 of the drawings shows a modified form of the brake shoe assembly in which registering oppositely faced wedge surfaces are circularly arranged within the brake shoes and are relatively rotatable by relative rotation of the brake shoes, these oppositely faced wedge surfaces taking the place of the inclined gear teeth of the helical or spiral gears 60 and 63.

As embodied, one of the brake shoes comprises a ring 100 which is U-shaped in section and provided on its outer flat surface with brake lining 101. The other brake shoe comprises a ring 103 which is also U-shaped in cross-section and of similar external diameter, being provided on its outer flat surface with a similar brake lining 104. The inner edge of ring 103 extends considerably further than the outer edge, and the inner edge extension 105 is interiorly finished so as to bear against the outer finished surface of the inner edge of ring 100, these surfaces forming a mutual bearing which holds the rings 100 and 103 coaxial while permitting their axial and relative rotational movement.

On the adjacent sides of rings 100 and 103, and positioned within the annular channel, are rigidly fixed the wedge rings 108 and 109, which may be and preferably are duplicates of each other, ring 108 being secured to brake ring 103 by screws 110, while the wedge ring 109 is secured to its brake ring 100 by the screws 111. Each of the wedge rings comprises a circular ring of substantial thickness, and formed on one face with a uniform series of relatively sharply inclined teeth 112, these teeth being uniform throughout its circumference, and of such a shape that they will fit in to the similar teeth of the cooperating ring mounted on the other brake shoe.

Thus, the rings 108 and 109, with their teeth in engagement as shown in Figure 6, hold the 75 brake shoes 100 and 103 only slightly spaced

apart, but as the brake shoes and rings are rotated in one direction relative to each other, the brake shoes 100 and 103 are expanded axially while reverse relative rotation of the shoes and rings causes axial contraction of the shoes.

The mounting and actuation of the brake shoes 100 and 103 may be identical with that of the other modification, and the two forms of brake shoes and expanding means are interchangeable with each other, and in fact are interchangeable with the corresponding parts shown and described in my copending application Ser. No. 263,347 filed March 22, 1939.

The invention in its broader aspects is not limited to the specific mechanisms shown and described but departures may be made therefrom within the scope of the accompanying claims without departing from the principles of the invention and without sacrificing its chief advantages.

What I claim is:

1. In a dual wheel assembly, the combination of a pair of independently rotatable dual wheels, a brake member attached to each wheel, a brake means mounted on a stationary member and movable into braking contact with the brake members and means rendered effective by contact of the brake means with one of the brake members while rotating for increasing the braking pressure between the brake means and both 30 brake members.

2. In a dual wheel assembly, the combination of a pair of independently rotatable dual wheels, a brake member attached to each wheel and spaced slightly from each other, cooperating brake means between the brake members and movable into braking contact with the adjacent faces of the brake members and means rendered effective by contact of the brake means with one of the brake members while rotating for increasing the braking pressure between the brake means and both 40 brake members.

3. In a dual wheel assembly, the combination of a pair of independently rotatable dual wheels, a brake member attached to each wheel and spaced slightly from each other, an expandible brake means between the brake members and movable into braking contact with the adjacent faces of the brake members and means rendered effective by contact of the expandible brake 50 means with one of the rotating brake members for increasing the braking pressure between the brake means and both brake members.

4. In a dual wheel assembly, the combination of a pair of independently rotatable dual wheels, an annular disc brake member attached to each wheel, the brake members being concentric and spaced apart from each other, expandible brake means between the brake members movable into contact with both brake members and means rendered effective by the contact of the expandible 55 brake means with a brake member while the brake members are rotating for increasing the braking pressure between the brake means and both brake members.

5. In a dual wheel assembly, the combination of a pair of independently rotatable dual wheels, an annular disc brake member attached to each wheel, the brake members being coaxial with respect to the wheels, spaced apart from each 70 other and mounted on one side of the wheels, expandible brake means between the brake members movable into contact with both brake members and means rendered effective by the con-

tact of the expandible brake means with a brake member while the brake members are rotating for increasing the braking pressure between the brake means and both brake members.

6. In a dual wheel assembly, the combination of a pair of independently rotatable dual wheels, a brake member attached to each wheel, the brake members being coaxial with respect to the wheels, spaced apart from each other and rigidly 10 secured to their respective wheels at one side of the wheel assembly, expandible brake means between the brake members movable into contact with both brake members and means rendered effective by the contact of the expandible brake means with a brake member while the brake members are rotating for increasing the braking pressure between the brake means and both 15 brake members.

7. In a vehicle wheel brake for dual wheels, a 20 pair of expandible disc-like brake members each adapted to frictionally engage a disc-like brake member, respectively carried by the two wheels which together form the dual wheel, and means for holding said first brake members in coaxial relation and for axially expanding said first brake 25 members, including inclined, interengaging and relatively rotatable members mounted on the first brake members.

8. In a vehicle wheel brake for dual wheels, a 30 pair of expandible disc-like brake members each adapted to frictionally engage a disc-like brake member, respectively carried by the two wheels which together form the dual wheel, a spiral internal gear member mounted on one of the first 35 brake members and a meshing spiral external gear member mounted on the other of the first brake members for retaining the first brake members in coaxial relation and for axially expanding the first brake members by relative rotation.

9. In a vehicle wheel brake for dual wheels, a 40 pair of expandible disc-like brake members each adapted to frictionally engage a disc-like brake member, respectively carried by the two wheels which together form the dual wheel, a circular 45 series of wedge members mounted on one of the first brake members, and a similar series of oppositely facing wedge members mounted on the other of the first brake members for axially expanding the first brake members by relative rotation thereof.

10. In a vehicle wheel brake for dual wheels, a 50 pair of expandible disc-like brake members each adapted to frictionally engage a disc-like brake member, respectively carried by the two wheels which together form the dual wheel, inclined interengaging members mounted on the first brake members for axially moving the brake members by relative rotation thereof, and means carried by said first brake members for retaining the first 55 brake members in coaxial relation.

11. In a vehicle wheel brake for dual wheels, a 60 pair of expandible disc-like brake members each adapted to frictionally engage a disc-like brake member, respectively carried by the two wheels which together form the dual wheel, inclined interengaging members mounted on the first brake members for axially moving the first brake members by relative rotation thereof, means carried by said first brake members for retaining the first 65 brake members in coaxial relation and a fluid pressure operated cylinder mounted on the first brake members for relatively rotating them.

CHARLES S. ASH.
